UNITED STATES PATENT OFFICE.

ROY I. RAPP, OF BLOOMFIELD, NEW JERSEY.

GREENHOUSE CONSTRUCTION.

Specification of Letters Patent.

Patented Oct. 7, 1913.

1,074,895.

Application filed December 12, 1910. Serial No. 596,853.

To all whom it may concern:

Be it known that I, ROY I. RAPP, a citizen of the United States, residing at Bloomfield, in the county of Essex and State of New Jersey, have invented certain new and useful Improvements in Greenhouse Construction, of which the following is a full, clear, and exact description, such as will enable others skilled in the art to which it

10 appertains to make and use the same.

This invention relates to the construction of greenhouses and other glass structures.

One of the objects thereof is to provide a simple, cheap and practically indestructible 15 sash-bar free from decomposable elements requiring frequent painting or coating.

Another object is to provide an all metal structure having such elasticity that expansion and contraction will be wholly absorbed 20 in the structure without subjecting the glazing medium to destructive breaking strains.

Another object is to produce a light durable building of the character described, in the erection of which time and cost will be 25 reduced to a minimum.

A still further object is to provide a simple and practical fastening means for securing the glass to the structural frame and to permit a slight relative movement upon expansion or contraction of these parts.

30 Other objects will be in part obvious and in part pointed out hereinafter.

The invention accordingly consists in the features of construction, combinations of 35 elements and arrangement of parts which will be exemplified in the construction hereinafter set forth, and the scope of the application of which will be indicated in the following claims.

40 In the accompanying drawings, wherein is shown one of many possible embodiments of my invention, Figure 1 is a vertical cross-section representing a portion of a greenhouse structure, built according to his invention; Fig. 2 is a combined perspective and cross-section showing a form of hollow metal sash-bar and the manner of attaching the glass thereto; Fig. 3 is a detail view of the construction employed in joining the 45 roof structure to a partition wall; Fig. 4 is a similar view showing the gable construction; and Fig. 5 is a cross-sectional view 50 taken on the line X-X of Fig. 1.

Similar reference characters refer to similar parts throughout the several views of the drawing.

This invention contemplates the use of continuous hollow metal sash-bars, preferably sherardized, galvanized or treated in any other suitable way, inside and out, to prevent 60 rust and corrosion thereof, and comprising inclined and vertical portions with a curved intersecting eaves portion. The sash-bars reach continuous from the foundation to the ridge of the roof or to the upper side of 65 the ventilating sashes. The glass extends longitudinally from the sill plate to the said ridge between successive sash-bars and is connected to the sash-bars in a manner to be 70 hereinafter described.

Referring to the drawings, 1 represents one of the sash-bars formed of metal sheeting and comprising, as shown in Fig. 2, a substantially flat portion 2, from which the metal is bent downwardly upon each side. 75 As the two sides are alike, a description of one thereof is deemed sufficient to give a full disclosure of the structure.

Extending downwardly from the edge of the portion 2 to a point 4, substantially midway of the depth of the bar, is a plane surface 3 which, at 5, is pressed inwardly to provide a fastening channel 6. From the point 4 the metal is bent outwardly and to a slight extent upwardly, to form a shoulder 7, the purpose of which will be herein-after described, and then the metal is bent again in a plane parallel to the portion 3. At the lower extremity the sheet is bent outwardly and upwardly to form a condensation groove 8. Each sash-bar is bent longitudinally in the form described above, the inclined portion providing the upper framework or roof of the greenhouse structure, the vertical part the side, and the connecting curved part is disposed at the point usually occupied by the eaves.

9 indicates the foundation, which may be of any suitable composition or construction, and surmounting the same is a cast iron sill 10, which may be secured by means of bolts 11 and a steel strap 12 to the grout, filling the space between the said sill and the top of the foundation. Each sash-bar is rigidly secured to the sill 10 by means of a cast 105 iron lug 13, which is provided with a portion adapted to fit snugly between the sides of the sash-bar and to be secured thereto by means of a bolt 14. The lug is secured to the sill by means of a bolt 15. Wherever 110 suitable, separator blocks 16 are bolted to the sash-bars, to which are attached, respec-

tively, the transversely extending purlins 17 and the angle-iron purlins 18. The latter members, occupying the same relative position upon opposite sides of the structure, are joined by tie-rods 19, which constitute an adjustable means for joining together the opposing members.

In Fig. 1 are shown ventilating sashes, each comprising a hollow metal bottom rail 20 and a hollow metal top rail 21. Connecting these rails are sash-bars 22 resembling in form those already described, by means of which the glass of the ventilating sash is held in position. Passing through the upper rail are separating members 23, which provide a rigid body, through which passes a bolt 24, by means of which the said rail is secured to a hinged butt 25, one half of which is bolted to the cast iron ridge member 26. This ridge member extends downwardly below the ventilating sash-rail and supports cast iron ridge brackets 27 to which the upper ends of the sash-bars 1 are bolted. The lower rail of the ventilating sash rests upon a hollow metal vent header 28, which is shown in cross-section in Fig. 1 and in longitudinal section in Fig. 5. The ends of each of these headers are cut to fit snugly against the respective sash-bars, between which they extend, and are fastened thereto by means of cast iron header lugs 29, which are formed to fit within the vent headers and to be bolted against a side of the sash-bar. These headers, which are substantially rectangular in cross-section, with the lower side open, are provided with upturned edges, forming troughs and a groove or channel 30 which receives the upper ends of the sheets of glass in contact therewith. The upper side is also provided with a groove 30' which serves to carry off any water collecting beneath the ventilating sash.

The manner of securing the glass plates or glazing medium 31 is best shown in Fig. 2, it being understood that the glass extends continuous from the foundation to the ventilating sash header and that each strip thereof, occupying the space between any two successive roof or sash-bars, may be composed of as many separate sheets as may be found desirable, glass of suitable curvature being provided to match the curvature of the sash-bars at the eaves. It will be seen that the edges of the adjacent glass plates or sheets are abutted so that the lower edge of each plate will lap over the upper edge of each adjacent plate, as is usual in greenhouse construction. It is to be noted that in securing the glass to the sash-bars the use of nails or other driven members is completely eliminated, thus removing one of the causes which tend toward glass breakage, particularly during the glazing operation, it being exceedingly difficult to drive 65 nails in a plane parallel with the glass, as

is the usual custom, without pressing upon and cracking the glass. In the present structure the glass plates rest upon the shoulders 7 and are firmly held thereon by means of spring steel clips 32 which are bent to provide a flat surface 33 adapted to press flatly upon the glass and two offset portions 34 and 35, formed at their ends to be sprung within the projecting edges of the channels 6, in which position they are securely held and exert a firm but resilient pressure upon the glass.

It will be obvious from a consideration of the character of the metal members and the manner in which the glass plates are secured thereto that the glass breakage and other ill effects occasioned by expansion and contraction of the various members under varying weather conditions will be reduced to a minimum, for the metal members provide elasticity within themselves and the spring clips permit of a limited relative movement of the glass with respect to the metal sash-bars, thus effectively attaining this desired end.

It will be noted that at the overlapping joints of adjacent plates, spring clips are employed which are cut away to press evenly upon both plates, as clearly shown at 36 in Fig. 1. Referring to Fig. 3, which discloses a partition construction, there is represented by 1' a roof member or sash-bar of slightly different form, having a portion 37 against which a relatively perpendicular sash-bar 1 is adapted to abut, and provided with downwardly extending portions 38 and 39 between which is positioned the upper end of the lug 40. A bolt 41 passing through the said lug and the portions 38 and 39 securely bind the lug and bar 1' together, and the lower portion of the lug, which extends downwardly between the sides of the sash-bar 1, is secured thereto by means of bolt 42. This construction answers the purpose of holding the glass of the roof and the partition in angular relation to each other. The gable construction shown in Fig. 4 is of a similar character, one side of the member 1" providing a support for the edge of the glass forming the roof and the other side of said member being formed to extend out and overhang the glass end wall of the structure, as shown at 45.

It will be seen from the foregoing that, in following out this invention, a structure is provided which is well adapted to attain, among others, all of the ends and objects hereinbefore set forth, in a thoroughly efficient and practical manner, and it may also be noted that because of the light construction employed, a minimum quantity of light will be obstructed, thereby greatly increasing, from a point of productiveness, the value of the greenhouse. It is further to be

noted that the strength and durability of the structure is greatly increased by the use of hollow metal bars in accordance with the disclosure of this invention; and the production of an inexpensive all metal and glass greenhouse construction is attained, wherein the use of wood is entirely eliminated.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters 25 Patent is:

In greenhouse construction, in combination, an integral hollow metallic arched sash bar, each side of the arch being provided with intermediate shoulders inclined to the adjacent portion of the arch, parallel concave clip retaining channels intermediate the upper and lower portions of the arch, each end of the arch being formed with an upturned portion providing a condensation 35 trough, and spring clips each having a flat portion adapted to press against the article to be held, and each comprising arms for engaging said retaining channels.

In testimony whereof I affix my signature, in the presence of two witnesses.

ROY I. RAPP.
